UNITED STATES PATENT OFFICE.

ISAAC RIVIN, OF CHAMBERLAIN, SOUTH DAKOTA.

GARMENT.

Application filed April 17, 1924. Serial No. 707,082.

The object of my invention is to provide a garment of the overall or unionall type, wherein the garment may be quickly and easily placed on the wearer without the necessity of employing buttons or other fastening devices.

Still a further object is to provide a garment having a pants portion and a pair of bands secured thereto and adapted to extend over the shoulders of the wearer, the bands being crossed over each other on the front and back of the wearer so that the crossed portions serve as the front and back of a jacket.

Still a further object is to provide sleeve elements on the shoulder bands, which are partially free therefrom so that the garment may be worn without any possibility of it binding under the arms of the wearer, and at the same time permits ventilation to a great extent adding to the comfort of the wearer of the garment.

Still a further object is to provide a modified form wherein a pair of side flaps are secured to the back side of the shoulder bands and arranged to be buttoned to the front sides thereof for protecting the sides of the wearer of the garment.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a perspective view of my improved garment, showing it in wearing position.

Figure 2 is a back view of my garment, the dotted line position showing the shoulder bands in the position they assume when the wearer is about to place the garment on him.

Figure 3 is a sectional view through the sleeve elements and through the shoulder bands showing the back portion of the same; and

Figure 4 is a perspective view of the shoulder bands and sleeve elements arranged in a slightly modified form.

In the accompanying drawings, I have used the reference character A to indicate generally a pants portion of my garment, which includes a pair of leg elements 10 separated on their front side as an ordinary pair of pants, as at 11.

The pants portion A is provided with a drop seat 12 having ordinary pockets 13 thereon. Hip pockets 14 are provided in the front side of the pants portion A. 60

The drop seat 12 is connected to the front side of the pants portion by means of buttons 15 arranged to extend through button holes formed in the front side of the pants portion. 65

The parts just described are of the ordinary construction.

Secured to the front side of the pants portion, near the upper edge thereof are the shoulder bands 16 and 17. The shoulder 70 bands are of substantial width, the purpose of which will be hereinafter more fully set forth.

The shoulder bands 16 and 17 are substantially half as wide as the front of the 75 pants portion, as clearly shown in Figure 1 of the drawings.

The shoulder band 16 may be properly termed as being fastened to the pants portion near the right hip of the wearer and 80 extends at an angle so that it passes over the left shoulder of the wearer of the garment.

The shoulder band 17 is secured to the pants portion A near the left hip of the wearer and passes over his right shoulder. 85

The back side of the shoulder band 16 is arranged at an angle and is secured to the drop seat 12 near the right hip of the wearer and the back of the shoulder band 17 is likewise secured to the drop seat 12 near 90 the left hip of the wearer.

From the construction of the parts just described, it will be seen that the shoulder bands 16 and 17 cross over each other on the front of the wearer and also on the back 95 of the wearer, thus forming a front and a back of substantial size, to protect the front and back of the wearer.

The shoulder bands pass over the shoulder of the wearer and are spaced apart so as to 100 provide a neck opening 18.

Sleeve elements 19 and 22 are secured to the shoulder bands 16 and 17 by means of the stitches 20 and 23. The sleeve elements are secured only a fraction of their entire 105 diameter to the shoulder bands so as to leave open portions 21 and 24 between the under-side of the sleeve elements and the shoulder bands.

The open portions 21 and 24 are so arranged that they come directly under the 110 arm pit of the wearer and do not cause the

sleeve element to bind but rather permit easy and free movement of the arms, and sufficient looseness so as to give the wearer of the garment as much comfort as possible.

- 5 The backs of the shoulder bands 16 and 17 are each formed with buttons 25 which extend through button holes 26 formed in the drop seat 12 for securing the shoulder bands to the back side of the pants portion.
- 10 The shoulder band 16 is provided with a pocket 27.

When it is desired to get into the garment, all that is necessary is to permit the sleeve elements and shoulder bands to assume the 15 position shown in dotted lines in Figure 2 of the drawings, and then slip the pants portion on the wearer.

Each shoulder band and sleeve is then brought into position where the arm of the 20 wearer extends through a sleeve element and the shoulder band rests upon the shoulder of the wearer. When the shoulder bands and sleeve elements are in the position shown in solid lines in Figure 2, then the 25 garment is complete and the parts will be kept in raised position.

It will be noted that the garment may be placed on the wearer without disconnecting the buttons 25 from the button holes 26, and 30 this is one of the big advantages of my garment.

It will be noted that the left side of the pants portion is supported by the shoulder on the right side, and the right side of the 35 pants portion is supported by the shoulder on the left side, thus giving the wearer of the garment much freedom of movement without the possibility of the garment binding either at the shoulders or sides.

40 In Figure 4 of the drawings, I have shown side flaps 28 and 30 secured to the shoulder bands 16 and 17 on their back side by stitches, and secured to the front side by buttons and button holes 29 and 31, as clearly illustrated in Figure 4 of the drawings.

The side flaps 28 and 30 tend to protect the clothing at the sides of the wearer.

Some changes may be made in the construction and arrangement of the various 50 parts of my invention, without departing from the real spirit and purpose of my invention and it is my intention to cover by my claims, any modified forms of structure

or use of mechanical equivalents which may be reasonably included within their scope.

55

I claim as my invention:

1. A garment of the class described comprising a pants portion, a pair of shoulder straps attached to the waist line thereof, one end of each strap extending from the 60 side of the pants portion to a point on the front of the waist where the straps slightly over-lap, and the other end of each strap extending from the side of the pants portion to a point on the back of the waist 65 where the straps slightly over-lap, said straps crossing on the chest and back of the wearer, and sleeves, secured along the upper half of the circumference of their upper ends to said shoulder straps.

70

2. A garment of the class described comprising a pants portion, a pair of shoulder straps attached to the waist line thereof, one end of each strap extending from the side of the pants portion to a point on the front of the waist where the straps slightly over-lap, and the other end of each strap extending from the side of the pants portion to a point on the back of the waist 75 where the straps slightly over-lap, said straps crossing on the 80 chest and back of the wearer, and side bands, secured to the back of each shoulder strap for covering the sides of the wearer, and having their free ends detachably secured to the front of each shoulder strap.

85

3. A garment of the class described comprising a pants portion, a pair of shoulder straps attached to the waist line thereof, one end of each strap extending from the side of the pants portion to a point on the front of the waist where the straps slightly over-lap, and the other end of each strap extending from the side of the pants portion to a point on the back of the waist 90 where the straps slightly over-lap, said straps crossing on the chest and back of the wearer, and sleeves, secured along the upper half of the circumference of their upper ends to said shoulder straps, and side bands secured to the back of each shoulder strap for covering the sides of the wearer and having their free ends detachably secured to the front of each shoulder strap.
